UNITED STATES PATENT OFFICE

JOHN O. BARCE, OF CHICAGO, ILLINOIS

SHOWER BATH CABINET

Original application filed August 19, 1929, Serial No. 386,758, and in Canada February 5, 1931. Divided and this application filed October 17, 1931. Serial No. 569,418.

My invention relates to cabinets and particularly to cabinets suitable as inclosures for shower baths and is a division of my copending application Serial No. 386,758.

In this type of cabinet which is usually placed in a room after the walls thereof have been either totally or partially erected, it is desirable to employ a sectional or knock-down construction in order to permit the cabinet to be shipped in knocked down condition and assembled in the room in which it is to be used. The structure should include as few parts as possible and the construction thereof should be of such a nature that it is possible to quickly and readily assemble the sections into a rigid inclosure with a minimum number of workmen. It is also desirable to have a structure which will be of such formation and construction to allow the use of enameled or porcelain coated sheet metal of relatively thin gauge. It is therefore the purpose of my invention to provide a cabinet involving these features and to provide such a cabinet which may be cheaply made upon a commercial basis and yet which will be of high quality and rigid construction.

In accordance with my invention the cabinet is formed of separate intersecting wall sections which may be joined together at the corners by any suitable means such as a locking strip which joins the strips together and conceals the edges of the adjoining walls. The walls are joined to and interlocked with the stiles which outline the entrance into the cabinet by a simple securing or clamping device, preferably formed integrally with the stile and comprising two spaced abutments on the stile between which the terminating marginal edge of the wall may be clamped, and which device also eliminates the necessity of separate means of attachment such as bolts or the like for securing the walls to the stiles. The lower extremities of the wall sections are preferably flanged in such a manner as to securely engage and interlock with a complementary formed receptor by being urged laterally thereagainst by means concealed within the stile and without the use of bolts or the like entering into the receptor. All marginal edges, where the porcelain or

other coating may not be perfect, are concealed from view to enhance the appearance of the finished cabinet.

A detailed description of one embodiment of my invention will be given in connection with the drawings in which:

Fig. 1 is a perspective view of a cabinet constructed in accordance with my invention.

Fig. 2 is a partial horizontal section illustrating one corner and stile showing the interior construction thereof.

Fig. 3 is a section on line 3—3 of Fig. 2 and further illustrates the interior construction of the stile.

Fig. 4 is a section on line 4—4 of Fig. 2 illustrating the inner end of the stile.

Fig. 5 is a perspective detail of the lower end of the stile member.

Fig. 6 is a section similar to Fig. 2 illustrating a modified form of a stile.

Fig. 7 is a perspective detail of the lower end of the stile member shown in Fig. 6.

Fig. 8 is a perspective of the abutment strip used in the modified form of stile construction illustrated in Figs. 6 and 7.

As shown in the illustrated embodiment the cabinet is of sectional construction made up of a rear wall 1, side walls 2 the latter of which in the present instance are bent at right angles to form front panels 3. The walls are preferably made of sheet metal, either enameled or coated with porcelain, secured together at their longitudinal edges by any desired means such as by a locking strip.

The walls are flanged inwardly at their lower ends to provide a seating flange 5 adapted to rest upon the top of the upstanding rim 6 of the receptor 7. The ends of the flanges 5 formed at the lower ends of walls 1, 2 and panels 3 are curved downwardly and outwardly as at 7, the latter curvature being complementary to the curvature of a ledge 8 formed on the rim 6 of the receptor. Due to the curved ledge and the curved flange formed upon the end of the walls the latter will be securely held against vertical movement in either direction and against horizontal movement in one direction when the walls are assembled and positioned with the lower flanged ends engaging the receptor. When

assembled the back wall and the outer ends of the front panels are held against inward movement and in contact with the receptor by the two side walls. At the same time the rear wall serves to hold the rear ends of the 5 side walls in contact with the receptor. The front ends of the side walls are held in position and against inward movement by the panels. To retain the inner ends of the front panels, and consequently all walls, tightly 10 against the receptor the free or inner ends of the panels 3 are flanged inwardly as at 9 which flange being beyond the inward flange 5 extends straight downwardly into a socket 11 formed in the receptor for the reception of 15 the stile members which will later be described. Disposed within sockets 11 are a pair of wedge blocks 12 similar in all respects to the usual form of locking blocks familiar in the printing art. These blocks 20 comprise generally a pair of wedges arranged with their inclined surfaces 13 contacting with each other and being rabbeted back at the top of their meeting faces to provide 25 spaced rack teeth 14 by means of which the wedge blocks may be moved relatively to each other by the use of the usual tool. In the present instance these blocks are inserted between the inturned flange 9 and the interior 30 of the socket 11 in the receptor in which the stile is set and are used to urge the panel 3 outwardly and cause the lower flanged end of the side wall to be forced tightly against the curved ledge 8. To wedge the blocks tightly, 35 the usual pinion key is meshed with rack teeth 14 and turned to slide the wedges longitudinally relative to each other along their inclined faces until adequate pressure is exerted against flange 9 to hold the side walls in place. Preferably the sockets 11 are drained by a 40 duct 16.

The entry into the cabinet is outlined by two stile members 17 which enclose the inner ends of panels 3. In the modification shown 45 in Figs. 1 to 5, inclusive, the stile members are formed of a single piece of sheet metal bent into a substantially rectangular form constituting an elongated tubular stile member the lower ends of which are adapted to enter the 50 sockets 11. Instead of the stile member however being of the usual substantially closed rectangular formation the front wall 18 is extended laterally beyond one side wall 19 and is then flanged inwardly as at 21 toward the rear wall 1 of the cabinet and the rear 55 wall 22 of the stile. The side wall adjacent flange 21 is shortened so as not to extend entirely to and meet the front wall 18. This construction leaves an opening 23 between the marginal edges of the stile and leading 60 into the interior of the stile. The marginal edges are preferably flanged inwardly as at 24 and 26 to form substantially parallel abutment surfaces. The depth of side wall 19 and 65 flange 21 is such that the two inturned flanges

24 and 26 are out of alignment a distance slightly less than the thickness of panels 3.

As previously stated the lower end of the stile is adapted to seat in the socket formed in the receptor. Consequently the lower end 70 of the front and one side wall is cut away as at 27 to clear the wedge blocks 12. Furthermore the side wall 19 which extends over the flange 5 is cut away as at 28 so that when the stile is inserted in place the lower end 75 of wall 19 will just engage the flange 5.

It follows from the above that when the stile is placed around the free end of panel 3 and rotated slightly to bring the edges thereof in alignment with socket 11 and pushed 80 in place the free edge of panel 3 will be securely gripped by the stile, that is, by the abutment flanges 24 and 26.

In the modification shown in Figs. 6 to 8, inclusive, the construction is generally the same as that shown in Figs. 1 to 5, there being a slight modification of the stile construction. In this modification the stile member instead of being of one piece is constructed in two pieces. As shown the stile member is constructed of a main panel or U-shaped member 29 which constitutes the outer member, and an inner V-shaped abutment member 31. As in the prior illustrations the front wall 32 of the stile is flanged rearwardly as at 33 and 34 then back upon itself as at 34 to provide an abutment surface. The rear wall 36 of the stile instead of being continued forwardly to provide a side wall as in the prior instance, is merely curled inwardly to provide a hook 100 37 leaving one side of the main member entirely open. To close the stile and to form a second spaced abutment a V-shaped abutment member 31 is provided having two inclined side walls 39 meeting in a flat relatively narrow apex or end wall 41. The spread of the side walls is such that their free ends engage in the hooked end 37 and the corner formed by the meeting of the rear and side walls of the stile, the spread being 110 slightly in excess so that the abutment member necessarily must be sprung to be inserted in position whereby it will remain in position by frictional contact. The height of the abutment member is such as to bring the apex 115 or abutment surface 41 parallel with abutment surface 34 but out of alignment therewith a distance slightly less than the thickness of the panel 3.

It follows from the above that as in the 120 modification shown in Figs. 1 to 5 the panel 3 will be gripped between the abutment surfaces 34 and 41 after insertion of the panel between the surfaces and a partial rotation of the stile to bring the front wall 32 substantially parallel with panel 3.

From the above description of my invention it is apparent that I have provided a cabinet involving a minimum number of parts and which may be assembled by a mini- 125 130

mum number of workmen. It will be observed that there are practically no sharp corners and that all marginal edges where the enameling or other coating may be thin or partly chipped are concealed.

In assembling the cabinet constructed as above described, the wall members are inserted in place from the inside rather than from the outside and the corners secured together as is usually the custom. The side walls will be held in position at the rear end by the rear wall. The front ends are held in place by the panels which are urged against the ledge of the receptor by the action of the wedge members forcing the ends of the panels outwardly. With the walls thus secured in place, the stiles may be set in position in their sockets to engage the inner ends of the panels. It will be noted that no bolts are used to secure the lower ends of the walls to the receptor nor the stiles to the walls or receptor.

It is obvious that minor changes may be made in the details of construction without departing from the spirit and scope of my invention as defined in the claims appended hereto.

I claim:

1. A hollow stile for use in cabinets or the like comprising an elongated hollow member formed by intersecting side walls, two of said walls terminating short of each other a substantial distance in one direction transverse to the length of said stile and a relatively smaller distance in a second direction transverse to the length of said stile.

2. A hollow elongated stile provided with a longitudinally disposed slot for the reception of the margin of an adjacent wall, said slot being defined by the edges of the stile walls, said edges terminating short of each other a substantial distance in one direction transverse to the length of said stile and a relatively smaller distance in a second direction transverse to the length of said stile.

3. A hollow elongated stile provided with a longitudinally disposed slot for the reception of the margin of an adjacent wall, said slot being defined by two abutment surfaces disposed relatively to each other a substantial distance apart in one direction transverse to the length of said stile and a relatively smaller distance apart in a second direction transverse to the length of said stile.

4. A stile for a cabinet or the like consisting of a metal sheet bent longitudinally into substantially rectangular form and providing a longitudinally extending slot in one wall thereof for the reception of the marginal edge of a side wall, said slot being defined by two abutment surfaces spaced from each other a substantial distance in one direction transverse to the length of the stile and a relatively smaller distance in a second direction transverse to the length of said stile.

5. A stile for a cabinet or the like consisting of a metal sheet bent longitudinally into substantially rectangular form and providing a longitudinal slot in one wall thereof for the reception of the marginal edge of a side wall, said slot being formed by an extension of one wall in a direction laterally beyond an adjacent wall, said adjacent wall being shorter than its opposite wall and said extended wall being bent toward the shortened wall.

6. A stile for a cabinet or the like consisting of a metal sheet bent longitudinally into substantially rectangular form and providing a longitudinal slot in one wall thereof for the reception of the marginal edge of a side wall, said slot being formed by an extension of one wall in a direction laterally beyond an adjacent wall, said adjacent wall being shorter than its opposite wall and said extended wall being bent toward the shortened wall, the terminating edges of said spaced walls being flanged to provide two substantially parallel spaced abutment surfaces.

7. A stile for a cabinet or the like comprising an elongated hollow member open upon one side, the free end of one wall thereof being flanged inwardly to form an abutment surface, an abutment member extending from the wall opposite said first mentioned wall and terminating in a second abutment surface substantially parallel to said first abutment surface and spaced therefrom a substantial distance in one direction transverse to the length of said stile and a relatively smaller distance in a second direction transverse to the length of said stile.

8. A hollow elongated stile for a cabinet or the like comprising a substantially U-shaped outer member having the free ends thereof flanged inwardly and an inner V-shaped member positioned with its free ends disposed between one inturned flange and one adjacent corner of said outer member, the apex of said inner member being disposed toward the opposite wall and terminating short of the opposite wall and within the free flanged end of the wall not engaged by the V-shaped member.

9. A cabinet or the like comprising intersecting walls and a receptor, the lower ends of the walls engaging the receptor, the marginal edges of two of said walls being enclosed in hollow stiles defining an entry into said cabinet and means within said stiles for locking the walls in engagement with said receptor.

10. A cabinet or the like comprising intersecting walls and a receptor, the lower ends of the walls engaging the receptor, the marginal edges of two of said walls being enclosed in hollow stiles defining an entry into said cabinet and means within said stiles for locking the walls in engagement with said receptor, said stiles being cut away at the low-

er ends thereof to accommodate said locking means.

11. A cabinet or the like comprising intersecting walls and a receptor, the lower ends of the walls engaging the receptor, the marginal edges of two of said walls being enclosed in hollow stiles defining an entry into said cabinet and means within said stiles for locking the walls in engagement with said receptor, said stiles being cut away at the lower ends thereof to accommodate said locking means and the engaging portion of said walls.

In witness of the foregoing I affix my signature.

JOHN O. BARCE.
